UNITED STATES PATENT OFFICE.

MIERS CORYELL, OF NEW YORK, N. Y.

FURNACE FOR STEAM-BOILERS.

SPECIFICATION forming part of Letters Patent No. 326,631, dated September 22, 1885.

Application filed January 26, 1885. (No model.)

To all whom it may concern:

Be it known that I, MIERS CORYELL, of the city and State of New York, have invented an Improvement in Furnaces for Steam-Boilers, 5 of which the following is a specification.

Practical experience has shown me that furnaces of boilers are greatly improved in efficiency by substituting brick walls for the water-walls at their sides and front ends, the 10 bricks serving to retain the heat and produce a more perfect combustion of the fuel, instead of such heat being absorbed and conveyed away, and thus lessening the intensity of the fire. The cooling effect upon the contents of 15 a furnace surrounded by water-walls is known to be injurious and fatal to economy, because the conductive power of the exposed metal of the water-wall carries into the water so much of the heat that the temperature is kept too 20 low for the complete combustion of coal. In boilers constructed with furnaces having brick sides and ends, there is a part of the cylindrical shell of the boiler itself, or water or fire tubes, as the case may be, which is directly 25 over the fire, or very close to or connected with it. This exposed heating-surface is of great conductivity, and absorbs the heat which is needed for the volatilization of the bituminous portion of the coal and its perfect combustion. 30 The heat should be retained and accumulated in order that the required temperature may be obtained for a perfect combustion and union of the carbon and oxygen—in other words, the furnace should be of a 35 non-conducting material, and should retain within it the whole of the heat until all the combustible products of the coals are thoroughly ignited. Then the highest temperature due to perfect combustion can be directed 40 upon and absorbed by the boiler heating-surface of whatever description.

My improved furnace is applicable to all types of boilers, and will in operation add to their efficiency, economy, and safety.

45 My invention will be readily understood by reference to the accompanying drawings.

Figure 1 is a front elevation of the boiler or boiler-front and doors. Fig. 2 is a transverse section at the line C C, Fig. 3. Fig. 3 is a longitudinal section at the lines A A B B, Fig. 50 2, and Fig. 4 is a horizontal section at the lines x x y y, Fig. 3.

D D are the furnace or fire chambers, and J 55 J the arches of brick, forming complete covers to the furnaces. These furnaces are constructed under the boiler-shell. In this form of boiler the arches screen the shell from the furnace heat. In other types they would screen the water-tubes or other heating-surfaces.

60 The bridge-wall is shown at E at the end of the grate-bars.

I have shown the side walls, K, of brick, 65 protecting the side portions of the boiler, so that the heat will not interfere with the downward circulation of the water at the sides of the boiler, and there are wing-walls T and an arch, M, to direct the products of combustion as they pass into the rear ends of the tubes.

The spaces between the tops of the arches 70 J and the under side of the boiler are open for the heated products of combustion to pass up to the boiler, and for the heat that is radiated from the arches to reach such boiler. Thereby the boiler will be kept in a heated 75 condition, and there will be no loss of heating-surface in consequence of the introduction of the brick arches, and the boiler will not be liable to injury from too great heat.

In order to maintain a gradual circulation 80 of the heated air between the boiler and the tops of the arches, I employ an opening through the front plate with a pipe and damper, V, leading into the bonnet at the base of the smoke-stack.

85 I do not claim a furnace having a brick arch extending over the fire and the whole length of the boiler, as this has been made.

I claim as my invention—

1. The combination, with the grate-bars, 90 bridge-wall, and boiler, of two continuous brick arches over the fire, said arches extending from the front wall to the bridge-wall, and forming a shield to prevent the direct action of the fire or products of combustion upon the 95 boiler, the space between the arches and the boiler being open at the back end for the heated gases to pass in and forward from beyond the bridge-wall and act upon the boiler, substantially as set forth.

100 2. The combination, with the grate-bars and boiler, of a bridge-wall, brick side walls, and a continuous brick arch over the fire-chamber, extending from the front wall without

openings to the bridge-wall, there being an open space between the arch and the boiler open at the rear to the flue beyond the bridge-wall, the wing-walls T near the back end of the boiler, and the arch M and return-flues, substantially as set forth.

3. The combination, with the arches over the fire-chamber and the boiler, of the pipe

and damper V, leading to the base of the smoke-stack, substantially as specified.

Signed by me this 7th day of January, A. D. 1885.

MIERS CORYELL.
